United States Patent Office

Des. 217,900

Patented June 30, 1970

217,900

DISPENSING PILL PACKAGE OR SIMILAR ARTICLE

Burton J. Gray, Valley Forge, Pa., assignor to American Home Products Corporation, New York, N.Y., a corporation of Delaware

Filed July 17, 1968, Ser. No. 12,800

Term of patent 14 years

Int. Cl. D9—99

U.S. Cl. D9—184

FIG. 1

FIG. 7

FIG. 4

8

8

FIG. 2

FIG. 3 FIG. 5

FIG. 6

FIG. 8

FIG. 1 is a perspective view of a dispensing pill package or similar article showing my new design, with the inner carrier partly removed from the outer sheath;

FIG. 2 is a top plan view in closed position, the bottom being plain and unornamented;

FIG. 3 is an edge view thereof;

FIG. 4 is an end view thereof;

FIG. 5 is a top plan view of the inner carrier;

FIG. 6 is an edge view thereof;

FIG. 7 is an end view thereof; and

FIG. 8 is a sectional view taken on the line 8—8 of FIG. 2.

The dominant features of my design reside in the portions shown in full lines.

I claim:

The ornamental design for a dispensing pill package or
